R. D. TOLMAN.

BALLOT COUNTING APPARATUS,
APPLICATION FILED OCT. 18, 1917.

1,319,255.

Patented Oct. 21, 1919.

UNITED STATES PATENT OFFICE.

ROY D. TOLMAN, OF WORCESTER, MASSACHUSETTS.

BALLOT-COUNTING APPARATUS.

1,319,255.

Specification of Letters Patent. Patented Oct. 21, 1919.

Application filed October 18, 1917. Serial No. 197,327.

To all whom it may concern:

Be it known that I, Roy D. TOLMAN, a citizen of the United States, residing at Worcester, in the county of Worcester, and in the Commonwealth of Massachusetts, have invented a new and useful Improvement in Ballot-Counting Apparatus.

My ballot counting apparatus has been designed for use in counting the number of votes received by each candidate upon Australian ballots in blocks of 50 or less. Its operation is well known to those familiar with this type of counter which has been in use in certain parts of the country. My ballot counting apparatus is a very compact instrument in comparison to others and it comprises only two individual sections, that of the clamping device and the straight edge. These two sections are locked together when sent to the polls and when they are not in use. The clamping device has the usual markings upon it to designate the proper even spacing of the ballots and means has been secured whereby the operation of clamping the ballots has been made very much easier and it obviates the danger of disarranging the ballots after they have been once laid in proper position. This counter will count ballots of any thickness. By making a counting apparatus of such compactness one is able to count the ballots while sitting at a table, the ballots at the start would simply lie over the edge of the table and as the counting proceeded the clamping device would be carried farther upon the table until the entire length of the ballot had been counted. Other features not mentioned here will appear in the following description and accompanying drawings.

Referring to the accompanying drawings, Figure 1 is a perspective view of my counting apparatus as assembled and ready for transportation to the polls. Fig. 2 is a perspective view of the same after being opened to place the ballots therein.

Fig. 3 is a perspective view of the counting apparatus with the ballots clamped therein and the straight edge in position to count the crosses upon the ballots.

Fig. 4 is an end view of the ballot counting apparatus in a position similar to that in Fig. 3.

Fig. 5 is an end view of the same but showing the apparatus reversed for counting the reverse side of the ballot and at the same time allowing the ballots to lie over the edge of the table.

My counter comprises a base board 10 having a longitudinal recess 11 cut therein whereupon the ballots 12 are evenly placed in proper position one to the other. All ballots previously having been opened and refolded so that the markings or crosses are visible they are laid in the recess 11, the first being laid up to first gage mark 13 which is 1, the second to mark number 2 and so on until all the ballots are placed corresponding to their proper marking one over the other. The last ballot forms the base from which all counting begins, for it is the topmost ballot. By using the straight edge 14 placed under any name at the base, it will be readily seen that the total number of crosses or votes for that individual candidate in that block of ballots can be easily tallied and checked up by running down along the straight edge 14 when in position as shown in Fig. 3.

The gage marks 13 are numbered every fifth one to facilitate the counting, especially of the odd block of ballots at the end where there are less than 50. In order to make it possible to handle a block of 50 ballots or less in my apparatus, I secure a clamping bar 15 upon the base board 10 in a position which will always insure its proper relation thereto as will be understood later. Upon the base board 10 I secure plates 16 which have thumb buttons 17 mounted thereon and which are capable of being adjusted by the convexity of the plates 16 together with the screws which pass therethrough. The thumb buttons are so placed as to project over the edge of the base board 10 and on to the top of the clamping bar 15 but in order to insure a perfect clamping effect upon the bar 15 and ballots 12, I find it best to have wedges 18 upon the clamping bar 15.

By this arrangement of clamping, I am certain of no displacement of any of the ballots. After all ballots have been placed in position ready for clamping, it is necessary to have the buttons 17 and wedges 18 so positioned that they will allow the clamping bar to come upon the ballots in position and clamp them at once without any un-

necessary moving around of the clamping bar 15 when lining up the wedges with the buttons. To accomplish this object I secure the clamping bar 15 to the base board 10 by 5 hinges 19 which will allow the bar to swing upon the ballots correctly without any end-wise motion and into a position always ready to be clamped.

At the same time these hinges 19 allow the 10 bar to swing out of the way and up from the recess 11 where it is in clamped position. The hinges 19 hold the bar 15 in a raised position when ballots are being inserted for counting.

15 Another advantage obtained is that the clamping bar 15 will never become separated from the base board during transportation to the polls and in short you have a counter with only two separate sections, the clamping bar and straight edge 14. This is a great 20 advantage in making sure that you have a complete outfit for counting the votes at the close of an election.

In constructing the straight edge 14, it 25 is desired to make an article which could be easily handled and at the same time placed in the apparatus so that it would not fall out and become lost. The straight edge 14 comprises a thin angle bar having its 30 ends turned up as shown at 20 so that when placed in position as in Fig. 1 between the base board 10 and clamping bar 15, it neither will be able to move lengthwise nor 35 sidewise but will be simply clamped by the thumb buttons 17 and ready for transportation to the polls.

After the ballots are ready to be counted 40 and have been clamped, I find it best to slightly tilt my entire counting apparatus in order to make certain that the entire exposed surface of the ballots come in contact with the table as near as possible. To accomplish this object, leveling plugs 21 are placed at the rear edge of the base board 45 10 so that they will tip the rear edge upwardly and bring the front edge nearer the table as shown in Figs. 4 and 5. This will make it possible to easily count the first few lines upon the ballots.

50 In counting the reverse side of the ballot when the apparatus is turned upon its face, as shown in Fig. 5 ordinarily without any tilting means, the ballots would not lie flat and it would be hard to hold the straight edge in position when the ballots were not lying flat upon some base, therefore in this position especially, it is necessary to tilt the base board 10 much more than on the other side. To secure this 55 extra amount of tilting, I use a tilting bar 23 in addition to the regular leveling plugs 21. When not in use this tilting bar 23 can be locked in position along the side of the clamping bar 10 as shown in Figs. 1 60 and 4 and thus will be out of the way until

needed. Emery is placed upon clamping bar 15 and in recess 11 in order to insure a better gripping effect upon the ballot when clamped.

Having described my invention in full, I 70 desire to claim by Letters Patent,

1. A ballot counting apparatus comprising a clamping device with clamping buttons, a bar with wedges held thereon and a straight edge adapted to be held therein. 75

2. A ballot counting apparatus comprising a clamping device with pivoted thumb buttons, tension plates held under the buttons and a clamping bar with wedges to be acted upon by said buttons. 80

3. A ballot counting apparatus comprising a clamping device with gage marks, a hinged clamping bar with wedges, thumb buttons acting upon said wedges and said hinged clamping bar so positioned as to allow the bar to be raised over and away from the gage marks and thumb buttons. 85

4. A ballot counting apparatus comprising a base board with a channel to receive a clamping bar, clamping mechanism and a straight edge adapted to be held between the base board and clamping bar. 90

5. A ballot counting apparatus having a clamping device with a clamping bar and a straight edge adapted to be clamped under 95 the bar.

6. A ballot counting apparatus having a clamping device with a bar adapted to be held under tension and a straight edge having its sides turned up in angular form 100 adapted to fit around the bar.

7. A ballot counting apparatus comprising a clamping means along the front edge adapted to hold ballots, and lugs attached adjacent to the rear edge of the apparatus 105 for elevating that edge and causing the exposed surface of the ballots to lie substantially in one plane.

8. A ballot counting apparatus comprising a clamping means having a channel 110 along one edge for the reception of ballots and a foot mounted upon the opposite edge adapted for supporting that edge in a raised position and thereby lowering the channel edge which is adapted to hold ballots, causing the exposed surface of the ballots to lie substantially in one plane. 115

9. A ballot counting apparatus comprising a channeled base board with clamping means and a straight edge adapted to fit 120 within the channel.

10. A ballot counting apparatus comprising a channeled base board having clamping means upon the upper side of one edge thereof and made thin at the lower side of 125 said edge, to permit the channeled portion to come into its lowest position.

11. A ballot counting apparatus comprising a base board having mounted upon one side clamping mechanism which is adjacent 130

to a channel for the reception of the ballots and a foot so placed as to raise the clamping mechanism upward and bring the exposed surface of the ballots held in the channel downward.

12. A ballot counting apparatus comprising a base board with a channel along one edge for the reception of the ballots, clamping mechanism upon one side of said edge and a beveled surface upon the other side, and lugs so placed at the rear of the clamping mechanism that the exposed surface of the ballots in the channel will lie substantially in one plane.

15 13. A ballot counting apparatus comprising a clamping mechanism along the front edge adapted to hold ballots and a raising

means along the rear edge so placed as to raise that edge and cause the ballots held in the clamping mechanism to lie substantially 20 in one plane.

14. A ballot counting apparatus comprising a registration device adapted to hold ballots, thumb buttons mounted upon the registration device and a swinging clamping bar having wedges, so arranged as to allow the bar to be brought onto the registration device and cause the wedges to come into operative position with said thumb buttons.
